UNITED STATES PATENT OFFICE.

JESSE H. WHITAKER AND FRANK H. HUBBARD, OF WASHINGTON, DISTRICT OF COLUMBIA.

TABULATOR FOR TYPE-WRITERS.

No. 874,272.

Specification of Letters Patent.

Patented Dec. 17, 1907.

Application filed February 6, 1907. Serial No. 353,031.

To all whom it may concern:

Be it known that we, JESSE H. WHITAKER and FRANK H. HUBBARD, citizens of the United States, residing at Washington, in the 5 District of Columbia, have invented certain new and useful Improvements in Tabulators for Type-Writers; and we do hereby declare the following to be a full, clear, and exact description of the invention, such as will enable others skilled in the art to which it app- 10 pertains to make and use the same.

Our present invention relates to typewriting machines, and has for its object to provide a cheap and efficient combination of de- 15 vices for effecting variable spacing in addition to the step-by-step feed, whereby bills and tabular statements may be readily written when this is desired.

In the drawings we have shown the best 20 form in which we have contemplated embodying our invention and said invention is disclosed in the following description and claims.

In the drawings, Figure 1 is a rear view in 25 elevation of a typewriter provided with our invention. Fig. 2 is a sectional view from front to rear of such a machine, and Fig. 3 is an isometric perspective view of the devices constituting our attachment detached.

To the back of the side standards of the 30 frame of a typewriter or to any other suitable stationary part of the typewriter, we attach a rod A. In this instance such rod is secured by brackets or clips a a. Upon this rod A is 35 mounted the lever B having its upper end elongated laterally to form arms at each side as shown in the drawings. This lever, which we term the release lever, is so mounted that it can rock or swing on the rod A and also 40 slide longitudinally thereon.

Above the upper end of the lever B is a 45 column stop bar C. This bar is rigidly secured to brackets c c' which extend downwards and engage the rod A in such way as to slide thereon. The lower ends of the brackets c c' extend inwardly and engage the sides of the lever B, so that when moving longitudinally of the rod both parts shall move together. The column stop bar and its sup- 50 porting parts are held from swinging or turning on the rod A in any preferred manner. In this instance it is shown as held from such movement by a rod a' extending inwardly from the clip or bracket a. This rod passes 55 through one of the supporting brackets of the column stop bar, so that the bar is per-

mitted a back and forth movement in a fixed vertical plane. This column stop bar may be of any preferred construction and is provided with stops c'' which may be moved 60 from place to place along said bar as desired in a well known way.

To the paper carriage of the typewriter is pivotally secured the stop lever D. This lever has its two arms extending approxi- 65 mately at right angles to each other. The one extending downwardly between the forward side of the lever B and the rod C' attached thereto and the other rearwardly over the column stop bar C. The down- 70 wardly extending arm is held by a rod C' extending parallel with the upper part of the lever B, so that the lower end of the lever arm is preferably near to but not engaging the upper end of the lever B. The other 75 arm is provided with a downwardly extending lug or projection d which is held normally above the stops c'' of the column stop bar C.

When the release lever is swung upon the 80 rod A so that its upper end moves forward it comes in contact with the downwardly extending arm of the lever D and presses it forward bringing the rearwardly extending arm of the lever downward and the projection d into the path of the stops on the stop bar. 85

In order that the paper carriage may move long distances or from any point to a predetermined point regulated by the stop bar and the devices for arresting the same, it must be freed from the step-by-step feeding devices. 90 We accomplish this by the following instrumentalities. Upon a suitable stationary part of the machine, we secure a bracket E. The lower portion of this bracket is constructed so as to permit it to be secured to 95 the part of the typewriting machine most convenient for the attachment of the bracket thereto. In this case the lower part is made in the form of a clip which is tightly secured upon a bar or rod E'. The upper part of 100 this bracket has an opening therethrough in which is mounted the gudgeon or journal e, which is held from rotation but is free to slide therein. A spring e' is placed on this gudgeon or journal at the rear of the bracket 105 and so arranged as to constantly tend to draw the journal towards the rear of the machine. The rear end of the journal e is preferably provided with an anti-friction roll to decrease friction and this lies in contact 110 with the front part of the lever B. We prefer to give the journal a short downward turn

and place the roll thereon as shown in the drawing, but any other preferred form may be employed. The downwardly extending arm of the lever D is provided in a similar manner with an anti-friction roll. On the forward end of the journal e is revolvably mounted the pinion F, which is provided on its forward end with the inclined portion f, which is placed but a little distance in rear of the rack bar G of the paper carriage, so that when the journal e is moved forward by the release lever, the incline will engage the under side of the rack bar and raise it out of engagement with its pinion and into engagement with the teeth of the pinion F. A pinion is preferably employed here as in other constructions for like purposes. It turns readily on its journal so that there is but little friction and the points of the rack teeth are subjected to less wear than if resting upon a cylindrical surface. In Fig. 3 the device for raising the rack is shown as a roller F' with the inclined or tapered portion f'. This construction can be used in place of the pinion F but the pinion is our preferred form.

It will be seen that when the lever B is swung upon the rod A so as to move the upper portion forward, the rack will be raised out of engagement with the step-by-step feeding devices and that the paper carriage is free to move until the projection d of the rearwardly extending arm of the lever D engages a stop of the column stop bar and then the two will move in unison until they both are by some means arrested. In order to move the lever B and to stop the lever, column stop bar and paper carriage at different points when a stop of the column stop bar is thus engaged, a further construction is employed which will now be described.

Beneath the machine are located the usual push keys or bars H. The rear ends of these push bars extend beneath the lower end of the lever B and each is provided with an upwardly extending lug or projection h. The lower end of the lever B is provided at the right-hand side of the machine with the downwardly extending lug b. The lower end of the lever B is normally held as far as it will move toward the right side of the machine with its lower end against the projections h of the push rods H by means of the spring I secured to the lug b and a part of the frame. When the lower end of the lever is moved backward by a push rod, it is carried back beyond all of the push rods except the one actuated. The lever is then free to be moved by the column stop bar towards the left side of the machine. The stop bar and the lever B can be thus moved until the lug b comes in contact with the side of the rear end of the actuated push rod when the movement of the lever, column stop bar and carriage will be arrested. When the push rod

is released the parts will return to their normal places. It will thus be seen that the push keys or rods themselves form the denominational stops and that these denominational stops taken with the column stop bar constitute a tabulator of the most complete character.

The spring I will ordinarily serve to return the push rods to their normal positions but we prefer to provide each of such push rods with a retracting spring h' and such springs may be conveniently applied to said push keys or rods near the front of the machine in a well known way as shown in the drawings.

The operation of the attachment will be readily understood from the foregoing description by those familiar with this class of devices. The respective parts will be relatively timed, so that the stop lever D will be in position to engage the stops of the column stop bar before the feed rack of the carriage is disengaged from the step-by-step spacing or feeding mechanism and on the return to normal position the rack will engage the pinion of the step-by-step feeding devices before the lever D will be disengaged from the stop of the column stop bar. This disengagement is effected by the rod C' which on the return movement of the lever engages the forward side of the depending arm of the lever D and effects its release from the stops of the stop bar.

What we claim and desire to secure by Letters Patent is:—

1. A tabulating attachment for typewriters, comprising among its members a longitudinally movable column stop bar having stops thereon adjustable in respect to said bar, means for detaching the paper carriage from its step-by-step feeding devices and connecting it with the stop bar for joint movement, and means for arresting said column stop bar, substantially as described.

2. A tabulating attachment for typewriters comprising among its members, a longitudinally movable column stop bar mounted on the frame of the machine and having stops thereon adjustable in respect to said bar, means for detaching the paper carriage from its step-by-step feeding devices and connecting it with the said column stop bar to move the latter and means for arresting the column stop bar, substantially as described.

3. In a tabulator for typewriting machines, the combination with a column stop bar, capable of an endwise movement, of a movable stop on the paper carriage normally out of operative relation with the said stop bar, means for detaching the paper carriage from its step-by-step feeding devices and for moving the stop on the carriage into operative relation with the stops on the column stop bar to cause the carriage and stop bar to

- move in unison, and means for arresting the movement of the column stop bar, substantially as described.
4. In a tabulator for typewriting machines, the combination with a column stop bar capable of endwise movement, a stop on the paper carriage movable in a single vertical plane in respect to the paper carriage and normally out of operative relation with the stop bar, means for detaching the said carriage from its step-by-step feeding devices and for moving the carriage stop into operative relation with the column stop bar to cause the two to move in unison, and means for arresting the column stop bar, substantially as described.
5. In a tabulator for typewriters, the combination with a longitudinally movable column stop bar having stops adjustable longitudinally of the same, a stop lever on the paper carriage normally out of operative relation with the stops of the column stop bar, means for releasing the carriage from the control of its step-by-step feeding devices and for bringing the stop lever of the carriage into operative relation with the stops of the stop bar to cause the carriage and stop bar to move in unison, and means for arresting the movement of the stop bar, substantially as described.
6. A tabulating attachment for typewriters, comprising a column stop bar movable in the same direction as the paper carriage but confined to a single vertical plane, a stop lever arranged to be secured to the paper carriage in a position to be normally out of operative relation with the stops of the column stop bar, a lever to move the carriage stop lever into operative relation with the stop bar to cause the carriage to engage with and move the stop bar, means actuated by said lever to disengage the carriage from its letter feeding devices, and a series of auxiliary keys to actuate said lever and arrest the movement of said stop bar, substantially as described.
7. A tabulating attachment for typewriters, comprising a column stop bar and means for releasing the paper carriage from its letter feeding devices, and causing it to engage and move the column stop bar, said means including a series of auxiliary keys each of said keys arranged to act as a stop to arrest the movement of said stop bar at varying distances from a predetermined point, substantially as described.
8. A tabulating attachment comprising a column stop bar having stops adjustable longitudinally thereof, means for releasing the paper carriage and causing it to engage with said stops of the stop bar and move the stop bar, said means including a series of auxiliary keys, each arranged to arrest the movement of said stop bar, substantially as described.
9. In a typewriter and tabulator, the combination with the paper carriage and its feeding mechanism, of a column stop bar normally at rest but movable in a single horizontal plane, and means for releasing the carriage from its feeding mechanism, and causing the carriage to engage with and move the column stop bar, said means including a series of auxiliary keys operable to cause the release of the carriage, and the stopping of the stop bar and carriage, substantially as described.
10. In a typewriter and tabulator, the combination with the paper carriage and its feeding mechanism, of a column stop bar mounted on the frame of the machine and capable of endwise movement in a single horizontal plane, and means for releasing the carriage from the control of its step-by-step feed, and causing it to engage with and move the stop bar, said means including a series of auxiliary keys each operable to cause the release of the carriage and the arrest of the stop bar at a different point, substantially as described.
11. In a typewriter and tabulator, the combination with the paper carriage and its feeding mechanism including a vertically movable rack on said carriage, of a sliding journal movable toward and from said rack and a revoluble device on said journal having a conically tapered portion to engage and raise said rack when moved toward the same, substantially as described.
12. In a typewriter and tabulator, the combination with the paper carriage and its letter feeding devices, including a vertically movable rack on said carriage, of a sliding journal movable toward said rack, a revoluble device on said journal having a conically tapered portion to engage said rack, whereby the rack may be raised by moving the said journal and revoluble device toward said rack and a lever for moving said journal, substantially as described.
13. In a typewriter and tabulator, the combination with the paper carriage and its feeding mechanism, of a movable stop bar normally stationary with respect to the paper carriage, a series of auxiliary keys, and means interposed between said keys and paper carriage to release the carriage from its feeding mechanism and cause the said carriage to engage and move said stop bar, said keys each acting to arrest the movement of the stop bar and carriage, substantially as described.
14. In a typewriter and tabulator, the combination with the paper carriage and its letter feeding devices including a vertically movable rack, of a sliding journal movable toward and from said rack, a pinion revolvably mounted on said journal, said pinion being provided with a conically tapered portion to engage and raise the said rack when

the journal is moved towards the same, substantially as described.

15. In a typewriter and tabulator, the combination with the paper carriage and its letter feeding devices including a vertically movable rack upon said carriage, of a pinion having a tapered or inclined end adjacent to the said rack, mounted on a journal movable towards and from the said rack and means for moving said journal to cause the inclined end of said pinion to engage and raise said rack, substantially as described.

16. In a typewriter and tabulator, the combination with the paper carriage and its letter feeding devices, of a stop bar having adjustable stops thereon, a stop lever on the paper carriage normally out of operative relation with the stops of the stop bar, the said stop bar being mounted on the frame of the machine and movable in the same direction as the carriage, but normally stationary, means for releasing the paper carriage from its letter feeding devices and bringing the carriage stop lever into operative relation with the stops of the stop bar to cause the carriage to move the stop bar when one of its stops is engaged, and means for arresting the stop bar at different points, substantially as described.

30. 17. In a typewriter and tabulator, the combination with the paper carriage, of step-by-step feeding devices, a stop lever and stop bar, the one secured to the carriage and moving therewith and the other movable in a single vertical plane in the same direction as the carriage, means for releasing the carriage from the step-by-step feeding device and for bringing the lever stop and stop bar into operative relation, and means for arresting the movement of the stop bar, substantially as described.

18. In a typewriter and tabulator, the combination with the paper carriage and its step-by-step feeding devices, of a stop bar mounted on the frame of the machine and movable in the same direction as the paper carriage, a stop lever pivoted upon said carriage, means for releasing the paper carriage from the control of its step-by-step feeding devices and putting the stop lever and stop bar in operative relation and means for arresting the movement of the stop bar, substantially as described.

19. In a typewriter and tabulator, the combination with the paper carriage and its letter feeding devices, of a stop bar having stops adjustable longitudinally of the same, said stop bar being mounted on the frame of the machine and movable in the same direction as the paper carriage, a stop lever on the paper carriage normally out of the plane of the stops of the stop bar, a lever for releasing the carriage from the letter feeding devices and bringing the carriage into operative relation with the stops of the stop bar, the construc-

tion being such that the releasing lever, stop bar and carriage shall move together when the stop lever engages a stop of the stop bar and means for arresting the movement, substantially as described.

20. In a typewriter and tabulator, the combination with the paper carriage and its step-by-step feeding devices, of a stop bar mounted on the frame of the machine and movable in the same direction as the carriage, a stop lever pivoted upon said carriage, a release lever, means interposed between said release lever and the step-by-step feeding devices whereby said release lever will take the carriage from its step-by-step feeding devices and throw said stop lever and stop bar into operative relation, and means for limiting the movement of said stop bar, substantially as described.

21. In a typewriter and tabulator, the combination with the paper carriage and its step-by-step feeding devices, of a stop bar mounted on the frame of the machine and movable in the same direction as the carriage, a stop lever pivoted upon said carriage, a release lever, means interposed between said release lever and the step-by-step feeding devices whereby said release lever will take the carriage from its step-by-step feeding devices and throw said stop lever and stop bar into operative relation, and means for simultaneously operating said release lever and putting into position a stop to limit the movement of said stop bar, substantially as described.

22. In a typewriter and tabulator, the combination with the paper carriage and its step-by-step feeding devices, of a stop bar mounted on the frame of the machine and movable in the same direction as the carriage, a stop lever pivoted upon the carriage, a release lever movable longitudinally of its axis in the direction of the stop bar, connections between said release lever and said stop bar whereby the same will slide together, means interposed between said release lever and the step-by-step feeding devices and means for operating said release lever to take the carriage from its step-by-step feeding mechanism and put said stop lever and said stop bar in operative relation and means for limiting the movement of said stop bar, substantially as described.

23. In a typewriter and tabulator, the combination with the paper carriage and its step-by-step feeding devices, of a longitudinally movable column stop bar normally disconnected from the paper carriage and stationary in respect thereto but movable in a single vertical plane, means for detaching the paper carriage from its step-by-step feeding devices and connecting it with the column stop bar for joint movement and means for arresting the movement of the column stop bar and carriage, substantially as described.

24. In a typewriter and tabulator, the combination with the paper carriage and its step-by-step feeding devices, of a column stop bar movable longitudinally in a single vertical plane, normally disconnected from the paper carriage to permit the paper carriage to move without moving said bar, means for taking the carriage from the control of its step-by-step feeding devices and connecting it with the column stop bar for joint movement and means for arresting the stop bar at a predetermined point, substantially as described.

25. In a typewriter and tabulator, the combination with the paper carriage and its step-by-step feeding devices, of a longitudinally movable column stop bar provided with stops adjustable in respect to said bar, said bar being supported on some stationary part of the machine, and normally disconnected from the paper carriage to permit the carriage to move independently of the stop bar for ordinary writing, and means for tak-

ing the paper carriage from the control of its step-by-step feeding devices and connecting it with the stop bar for joint movement, substantially as described.

26. In a typewriter and tabulator, the combination with the paper carriage and its step-by-step feeding devices, of a longitudinally movable column stop bar, provided with column stops adjustable in respect to said bar, means for taking the carriage from the control of its step-by-step feeding devices and connecting it with one of the stops of the stop bar including means for arresting the stop bar at different points, substantially as described.

In testimony whereof we affix our signatures, in the presence of two witnesses.
